A.C. Bartram's Design for a new vase
Patented Feb. 11, 1867. 252

Des. 872

A. C. Barstow, of Providence, R. I
Letters Patent No. 872 Dated Feb. 17th 1857

The Schedule referred to in these Letters Patent and making part of the same.

To all persons to whom these Presents shall come.

Be it known that I, A. C. Barstow, of Providence in the County of Providence, and State of Rhode Island, have produced a new and original design for the front and side plates of a wood stove and I do hereby declare that the said new design is fully represented and described in the following specification and accompanying drawings to which reference is hereinafter made.

In the accompanying plate of drawings.

Fig. 1, is an elevation of the front plate of the stove,

Fig. 2, an elevation of the side plate, and

Fig. 3, a horizontal section of the same taken in the plane of the line A B, Fig. 2.

The panel of the side plate, fig. 2 is ornamented in the centre with a figure composed of rays a, a &c, arranged in an oval shape. From this oval figure as a centre radiate the elliptical waves b, b &c. Around the outer wave are placed small elliptical figures c, c &c, composed of the rays

a, a, like the central ornament. From the four corners of the panel proceed the rays d, d &c. The top of this plate has on it a cornice composed of mouldings e, e, and on the ends pilasters f, f. This plate is of a convex shape as shown in fig.

3.

The front plate, fig. 1, of which this fuel door forms a part, has on it the central ornament a, a, small elliptical waves b, b, the oval figures c, c, the corner rays d, d, and the pilasters f, f.

Having thus described my new design, I shall state my claim as follows.

What I claim as my invention or production and desire to have secured to me by Letters Patent, is

The new design for a stove consisting of the ornamental configurations herein above described and represented in the drawings.
